UNITED STATES PATENT OFFICE.

EDWARD B. STILSON, OF LESLIE, MICHIGAN, ASSIGNOR OF ONE-HALF TO
J. B. DE LAMATER, OF SAME PLACE.

DRAG-SAW.

SPECIFICATION forming part of Letters Patent No. 271,149, dated January 23, 1883.

Application filed September 30, 1882. (No model.)

To all whom it may concern:

Be it known that I, EDWARD B. STILSON, of Leslie, in the county of Ingham and State of Michigan, have invented certain new and useful Improvements in Drag-Saws; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved drag-saw. Fig. 2 is a side view of the same with the saw raised off the log, and Fig. 3 is a side view with the saw hung in position for transportation.

Similar letters of reference indicate corresponding parts in all the figures. 20 My invention has relation to drag-saws; and it consists in the improved construction and combination of parts of the same, as herein-after more fully described and claimed.

In the accompanying drawings, the letter A 25 represents the frame.

In bearings at the apex of the frame is pivoted the bar B, which forms the fulcrum for the lever C, to the end of which bar D is hinged. The saw E is fastened in the end of this bar 30 by bolts or screws, or by any other suitable means.

The two handles F and G are fastened to the lever C, one just above the fulcrum-bar B and the other some distance below it, and 35 are braced and held together by a rod, H, passing from the upper handle, F, through the lower one, G, to the lower end of lever C.

At the base of the frame, where the sawyer stands, is a board, I, hinged. This board, which 40 has a slot, J, in its inner end, serves a double purpose—viz., to hold the frame steady while sawing, by the sawyer standing on it, and to hold the free end of handle G in the slot J when it is pressed down to raise the saw off 45 the log, as shown in Fig. 2. The saw is guided in the log by the guide K, which consists of a rod bent to form a slot at its doubled point and hinged at its free ends to the front of the frame.

The doubled part of the guide (designated as 50 *k* in the drawings) has two functions—to guide

the saw in the part of it which is turned up and rides on the back of the saw, and to engage with a pin, f, at the inner end of the saw, by which the saw is raised off the log when the handles are pressed down, and may be 55 held in this position by turning board I up and holding the free end of the handle G in the slot J.

One or two dogs, L, are hinged to the sides of the frame, and are used to hold the log in 60 position for sawing.

Across the front part of the frame is a cross-bar, M, on which slides a hook, N, by which the saw is held when the machine is moved.

By the foregoing description, taken in connection with the accompanying drawings, the advantages of my saw will be easily seen. By having the two handles F and G placed one above the other, and the longer one below the shorter, the sawyer has a better position for 65 exercising all his strength to the best advantage in working them than by only using one handle. The combination of the pin f, engaging with the guide when the handles are pressed down and the lower one is held in 70 place by the slotted board I, brings the saw out of the way when the log requires handling, and prevents any accident by the handle G being held fast in the slot of board I when it is turned up, as plainly shown at Fig. 2. 75

Having thus described my invention, I claim and desire to secure by Letters Patent of the United States—

1. In a drag-saw, the combination of the saw E, having pin *f* at its inner end, pitman D, 85 lever C, and handle G, fastened upon the lever, guide K, hinged to the front part of frame A, and having upturned doubled end *k*, and foot-board I, hinged to the lower rear part of frame A, and having slot J, substantially as 90 and for the purpose shown and set forth.

2. In a drag-saw of the described class, the lever C for operating the saw, provided with a short and a long handle, F and G, connected to each other and to the lever by the oblique 95 brace-rod H, in combination with the hinged and slotted foot-board I, adapted to engage the free end of handle G, substantially as and for the purpose herein shown and described.

3. In a drag-saw, the combination of the 100

frame A, fulcrum-bar B, pivoted in the apex of the frame, lever C, fastened to the fulcrum-bar, handles F and G, fastened to the lever, and having brace H, pitman D, saw E, having pin 5 f at its inner end, guide K, hinged to the front of the frame, and having bent doubled end k, dog L, hinged to the frame, and foot-board I, hinged to the lower rear part of the frame, and having slot J, all constructed and combined

to operate substantially as and for the purpose to shown and set forth.

In testimony that I claim the foregoing as my own I have hereunto affixed my signature in presence of two witnesses.

EDWARD B. STILSON.
